METHOD AND APPARATUS FOR REFRIGERATING AND CARBONATING

Justus C. Goosmann, Chicago, Ill.

Application May 10, 1930. Serial No. 451,244

17 Claims. (Cl. 62—91.5)

This invention relates in general to a method and apparatus by means of which liquids and solids may be refrigerated and, if desired, liquids carbonated.

5 One of the objects of this invention is the provision of a refrigerating and carbonating apparatus employing a solid refrigerant, such as solid carbon dioxide.

10 A further object of this invention is the provision of an apparatus by means of which a solid refrigerant, such as solid carbon dioxide, is changed to the gaseous phase, then changed to the liquid phase, employed as a refrigerating medium while in the liquid phase and then 15 changed again to the gaseous phase to be used for impregnating and carbonating purposes.

15 A further object of this invention is the provision of an apparatus for utilizing refrigerating media, such as carbon dioxide, in accordance with 20 the above phase changes.

25 A still further object of this invention is to employ a refrigerating apparatus employing solid carbon dioxide or similar solid refrigerating media and a circulating liquid refrigerant.

30 These and many other objects as will appear from the following disclosure are attained by means of the method and apparatus of this invention.

35 This invention resides substantially in the combination, construction, arrangement, relative location of parts, steps and series of steps, all as will be explained in greater detail hereinafter.

Referring to the drawings:

Figure 1 is a diagrammatic view with some 35 parts in cross-section of a combined refrigerating and carbonating or impregnating apparatus;

Fig. 2 is a diagrammatic view with parts in cross-section of a refrigerating apparatus employing a solid refrigerating medium and a liquid circulating medium.

Fig. 3 is a diagrammatic view with some parts in cross-section of a modified form of refrigerating apparatus employing the principles of this invention.

45 The prime purpose of this invention is to provide a refrigerating and liquid impregnating or carbonating apparatus for the use of a solid refrigerating medium such as, for example, solid carbon dioxide or other solidified gases. In the 50 form of apparatus shown in Fig. 1, both refrigerating and liquid impregnating apparatus have been shown in a single system, but it is, of course, apparent that a complete system employing the principles of this invention need only comprise 55 either the refrigerating apparatus alone or the

liquid cooling and impregnating apparatus alone. In the apparatus in Fig. 2, a solid refrigerating medium is employed in conjunction with a liquid circulating medium of different characteristics. Thus the solid refrigerating medium can be solid 60 carbon dioxide, and the liquid circulating medium can be ethane, ethyl or methyl chloride, sulphur dioxide or, in fact, any other suitable liquid.

The apparatus and method of this invention will be best understood by direct reference to 65 the disclosure in the drawings and a description of the operation of the apparatus disclosed therein. At 1 is shown a suitably constructed chamber which may be in best practice covered with heat insulating material. This chamber is 70 provided with a cover 2 which may be closed in gas tight relation with the chamber by means of any suitable locking mechanism 3. The confined volume formed by this closed chamber has been indicated by the reference letter A. At 4 75 is a pressure control valve connected to the interior of the chamber and of adjustable construction, so that it will automatically maintain any desired gas pressure within the chamber. Such a valve is of well known construction in 80 many forms and need not be described in detail here. Near the top of chamber 1 is an exit port 5 to which is connected a pipe 6 which terminates in the cylinder of pump 7. Pump 7 is of the ordinary type which takes in the medium being 85 pumped on the suction stroke and expels it on the compression stroke. The delivery port of the pump is connected by pipe 8 to one end of the pipe coil 9 disposed within chamber 1. The other end of the coil 9 is connected by pipe 10 to the 90 inlet of the float valve 14. The float valve 14 is shown disposed within the refrigerating chamber 13. At 12 is diagrammatically illustrated a fluid pressure operated switch which controls the circuit for the motor which operates the 95 pump 7. The fluid pressure actuated switch 12 has been shown diagrammatically, since many forms of it are well known in the art. A pipe 11 extends from pipe 10 to the fluid pressure actuated member of switch 12.

100 The outlet port of the float valve 14 is connected to one end of the refrigerating coil 15. The other end of these coils is connected to the thermostatic valve 16 which has also been disclosed diagrammatically, since numerous forms 105 of it are well known in the art. A thermostatic tube 17 exposed to the temperature within the refrigerating chamber 13 is connected to the thermostatic valve in a manner obvious to those skilled in the art. The confined space provided 110

by the refrigerating chamber 13 has been indicated by the reference letter B. Valve 16 is connected by pipes 18 and 20 to the outlet port of another float valve 21. An adjustable pressure controlling valve 19 is connected in the pipes 18 and 20 to permit exhaust of gas under pressures in excess of those for which the valve is set. The inlet port of float valve 21 is connected to pipe 10 by pipe 22. At 23 is a liquid cooling 10 and gas impregnating or carbonating tank. This tank is divided by means of the wall 25 into a lower chamber C and an upper chamber D. The wall 25 has an opening through the center as is clear from the drawings. Arranged in chamber 15 C is a pipe coil 24 which is connected at one end to pipe 20. A liquid inlet connection to chamber C is shown at 26. At 27 is a thermostatic valve which connects with chamber C through pipe 28 and which also connects with this chamber through passage 29, so that the fluid in chamber C may flow through valve 27 to control its operation. It has the purpose of controlling the flow of refrigerant through coil 24 with 20 relation to the temperature of the liquid in chamber C.

The outlet of coil 24 is connected to pipe 30 through valve 27. Pipe 30 is connected to pressure regulating valve 46. This valve is provided with a pressure gauge 47 and is connected to chamber 35 D by pipe 48. Near the bottom of chamber D is the fluid outlet pipe 50. 31 represents a closure member which fits over the opening of wall 25. The closure member 31 is secured to a vertical pipe 32 which opens into chamber C at its lower end. In this pipe is a valve 34 which is operated by means of the float 33 which slides vertically on pipe 32. The valve 34 is operated by lever 38 which is connected by the link 37 to lever 36 which is pivoted at one end on the float and at its other end on link 35 which in turn is supported at its upper end on the pipe. The top of tank 23 is provided with a cover 43 through which extends a centering and securing means for the upper end of pipe 32. This means consists of a rod having a conical end 45 for engagement with the upper end of pipe 32 and for closing the end thereof. The rod is operated by the hand wheel 44 and may be moved vertically by reason of its threaded engagement with the hole in the cover through which it passes. Secured to the vertical pipe 32 are a series of pans. The pans 40 are of smaller diameter than the pans 41 which are disposed under them. Openings 39 are provided in pipe 32 just above the pans 40. Near the top of the casing 23 is provided a gas blow-off valve 42 which may be adjusted to maintain any desired gas pressure within chamber D.

It may be well to briefly point out here that the pressure regulating and gas blow-off valves 4, 19, 42 and 46 are of the same construction. These valves are very well known in the art and are usually but not necessarily of the diaphragm type which may be adjusted so that they will not operate to permit the escape of gas or liquid until a predetermined pressure is exceeded. Likewise, the float valves 14 and 21 are of usual and well-known construction for maintaining a predetermined liquid level. The thermostatic valves 16 and 27 are also of well-known construction as is the thermostatic control tube 17.

The operation of this apparatus is as follows: First, it may be pointed out that refrigerating chamber B may be used in the system without the liquid cooling and impregnating tank 23. Like-

wise, the refrigerating chamber B may be eliminated and only the tank 23 employed. They are both shown in the same system to illustrate the economy of the present invention in utilizing one source of solid refrigerating medium for refrigerating, cooling and impregnating materials.

While the operation of this apparatus will be described in connection with solid carbon dioxide, it may be pointed out that any suitable solidified gas may be employed. Solid carbon dioxide is placed in chamber A in the form of small pieces or lumps which are piled within and around the coil 9. Cover 2 is then closed and sealed by means of the locking means 3. As the solid carbon dioxide evaporates the gas formed is withdrawn through port 5 and pipe 6 by means of pump 7. The gas is compressed and delivered through pipe 8 to coil 9. This gas travelling through the coil 9 embedded in the cold solid carbon dioxide is condensed. The heat of compression taken on by the gas is exchanged through the walls of coil 9 and supplies the heat of vaporization for the solid carbon dioxide. As a result the gas in coil 9 is sufficiently chilled to liquefy it. As an actual matter of fact, coil 9 may be called a condenser coil. It may be well to point out here that although a pump 7 is shown for insuring circulation of the gas and liquid, it is not essential since such circulation may be secured by the temperature gradient in the cycle, as will be described in connection with Figure 3.

In other words, the gas produced in chamber A could be directly conducted into coil 9 through which it will flow downwardly and condense by reason of its own pressure. However, to accelerate the flow of the medium and to insure definitely the change in condition from vapor into liquid, the use of a compressor, such as illustrated, is at least desirable even if not entirely necessary. The valve 4 acts to maintain a predetermined gas pressure within the chamber A and permits the escape of excess gas when this pressure is exceeded. The condensed liquid then flows down through pipe 10. If the pressure in pipe 10 exceeds a predetermined amount, the pressure actuated switch 12 opens a circuit to the motor which drives the compressor shutting it down until such time as the pressure within pipe 10 falls sufficiently to permit switch 12 to close. The liquid flowing through pipe 10 is delivered to both float valves 14 and 21. These float valves maintain a predetermined liquid level therein and allow the wet vapors coming off the liquid to enter the cooling pipes 15 and 24. The cold liquid in pipe 15 serves to cool chamber B, and similarly the liquid in coil 24 cools the liquid in chamber C which is delivered therein through pipe 28. This liquid may, for example, be water which it is desired to carbonate. The temperature in chamber B is controlled by thermostatic valve 16 which receives the vapors coming from coil 15. A further control is effected by the thermostatic tube 17 which is located within chamber B so as to be subject to the temperature therein. The gases which exit from the thermostatic valve 16 are conducted through pipes 18 and 20 to the coils 24. Any surplus gas in these pipes is expelled through the exhaust valve 19. The gas and liquid carbon dioxide delivered to coil 24 serves to cool the water as it passes through chamber C.

The dry carbon dioxide gas coming from coil 24 is then conducted through pipe 30 to the pressure regulating valve 46 which is so adjusted as to deliver gas into chamber D at the proper

carbonating pressure. It is interesting to point out here that as is well known, the cooler a liquid is the more easily it may be impregnated with gas for a given pressure. Thus the cooling coils

5 24 are utilized to chill the water to be impregnated with gas to thus aid in its absorption of gas in chamber D. The water passes from chamber C upwardly through pipe 32 and is delivered into pans 40 through openings 39. It then trickles over the edge of pans 40 into pans 41 and falls over the edge of them to the bottom of chamber D. During this movement of the water, carbon dioxide gas from chamber D is absorbed by it. Float valve 33 operates to maintain a desired 10 water level within chamber D. The gas impregnated or carbonated water is drawn off through the discharge pipe 50. As pointed out before, valve 42 acts to relieve chamber D of any excessive pressure. The outlet from coil 24 is also controlled by the thermostatic valve 27, as well as the pressure regulating valve 46, and since the gas volume coming through the refrigerating coils is ample a constant gas pressure is maintained in chamber D.

25 It is only when both float valves 14 and 21 are shut off that the pressure in pipe 11 builds up sufficiently to open switch 12.

It will be apparent then by means of this apparatus that solid carbon dioxide may be employed to do useful refrigerating work in the most effective manner.

The apparatus shown in Fig. 2 comprises a refrigerating chamber 60 within which materials to be kept cool may be placed. A smaller closed chamber 61 is provided either within or outside of the chamber 60 and within which solid carbon dioxide in the form of small pieces may be placed. Within chamber 61 is a pipe coil 62 which is connected by pipe 63 to the cooling coils 64. The outlet of cooling coils 64 delivers into a float valve chamber 65 through a small control valve 67. The valve 67 is operated by means of a suitable float 66 by means of which the desired liquid level may be maintained. Another refrigerating coil 68 is connected at one end at the top of the float valve and at the other end with the top of coil 62. A thermostatic control device of well-known construction indicated at 69 is connected to the coil 68 and arranged so as to be subject to the temperature within the refrigerating chamber 60. A suitable refrigerating liquid, such as already disclosed as, for example, ethane, is provided within the coils 62, 64 and 68. The vapors given off by this liquid 55 pass from float valve chamber 65 into pipe coil 63. This gas is relatively cold and acts to chill chamber 60. The gases then flow into coil 62 where they are liquefied by reason of their loss of heat to the solid carbon dioxide within chamber 61. The liquid then flows down through pipe 63 into the float valve. Employing a float valve in the manner disclosed makes it possible to deliver to coils 68 the cooling medium in the form of wet vapors which come off the surface of the 60 liquid body within the valve. The thermostatic control valve 69 shuts off the circulation in the coils when the temperature in the cabinet is at a sufficiently low value. When the temperature rises above a predetermined value, the valve 65 opens to again permit circulation in the pipes.

70 It is apparent that there is no moving force in a system of this type other than that produced by the temperature difference in the solid carbon dioxide casing and the air in the outer cabinet 60. With this arrangement, there are

practically no moving parts and no apparatus, such as pumps and motors, required to effect its operation.

A still further modified form of construction employing the principles of this invention has been set forth in detail in Fig. 3. The well-known second law of thermo-dynamics states that heat cannot be transferred from one condition of temperature to a higher temperature condition without the expenditure of external energy. In this modified form of device an arrangement has been provided in which the heat abstracted from the space or materials being refrigerated is employed in the heat cycle of the device for doing useful work. Thus the very heat which is removed from the space or substance being refrigerated, as being undesirable, is given useful work to do in this apparatus.

Referring particularly to Fig. 3, at 60 has been shown the refrigerating chamber which may itself be chilled or, for example, it may be a room in which materials to be chilled are placed. At 61 is a closed metallic receptacle which, of course, in practical construction will be made so that the cover may be easily placed on and removed therefrom. The essential thing is that this chamber be gas tight when in use. Within the chamber is the condensing coil 62 which is open to the interior of the chamber at its upper end through the inlet 76. The lower end of the condenser coil is connected by pipe 63 to the liquid cooling coils 64. Liquid coils 64 delivered into the float valve 65 and the delivery of liquid thereto is controlled by the valve 67 and the float mechanism 66. Connected to the top of the float valve is a discharge pipe which is connected to the cooling coils 68. The upper end 77 of the cooling coils 68 connects with one end of the coil 78 which encircles the metallic chamber 61 in close proximity or in actual contact therewith. At 79 is the delivery pipe from the coil 78. Chamber 61 and its surrounding coil 78 are preferably enclosed within a casing of heat insulating material of any suitable type, as shown at 75. Although the chamber 61 has been shown within the cabinet 60, it is not at all necessary to place it therein, although it is desirable to do so. The outlet of coils 68 is controlled by means of the thermostatic valve 69 which is subject to the temperature within the cabinet 60. By means of this control valve the flow of vapor from the coils 68 is interrupted when the interior of the cabinet and its contents are at a predetermined temperature.

In operation, lumps of solid refrigerant are placed within chamber 61 and around the condensing coils 62. The vapor coming off from the refrigerant, which may be solid carbon dioxide, passes into the condensing coil 62 through the inlet 67. As in the case with chamber 1 of Fig. 1 and chamber 61 of Fig. 2, the temperatures and pressures within chamber 61 of Fig. 3 are such that the gas, given off by the carbon dioxide, as it flows through the condensing coil 62 is condensed into liquid form. The liquid flows through pipes 64 effecting some refrigeration and is delivered into the float valve where the liquid is maintained at a substantially fixed level. The wet vapors given off by the liquid flow through coil 68 to absorb heat from the chamber 60 and any materials therein. The wet vapor is, of course, raised in temperature by absorption of heat and becomes relatively warmer and a substantially dry vapor. The relatively warm vapor then flows through the coil 78 and supplies heat to the chamb-

ber 61 to effect further evaporation of the solid carbon dioxide therein. The gas is then delivered through outlet 79 either to the atmosphere or to a suitable container or receptacle or even to a 5 gasometer. With this arrangement then it will be apparent that the heat which is abstracted from chamber 60 and the articles therein by the vapor in coils 68 is employed to do useful work in effecting more rapid evaporation of the solid 10 carbon dioxide in chamber 61.

In the systems disclosed, it is apparent that the apparatus is adaptable for use in effecting low temperature refrigeration within stationary or portable refrigerators, such as those used in the 15 home or on trucks, refrigerator railway cars and other carriers. In fact, the principles of this invention may readily be applied to any form of refrigerating chamber and gas impregnating or carbonating apparatus.

23 It will be apparent from the foregoing disclosure that I have devised an apparatus involving certain principles of construction and operation which may be embodied in many physical forms without departing from these principles, I do 28 not therefore, desire to be strictly limited to the disclosure given for purposes of illustration, but rather to the scope of the appended claims.

What I seek to secure by United States Letters Patent is:

33 1. The method of preparing a liquid cooling medium for refrigerating purposes by utilizing a solid refrigerant which sublimes, comprising the steps of sublimating a solid refrigerant and circulating the gas formed in heat exchange relation with the remaining medium to effect condensation of the gas to liquid form to provide a 38 liquid cooling medium.

2. The method of employing solid carbon dioxide for refrigerating purposes comprising the 40 steps of sublimating a mass of solid carbon dioxide, circulating the carbon dioxide gas formed through the remaining mass, and condensing the circulating gas to form liquid carbon dioxide for cooling purposes by heat exchange with the 45 remaining mass.

3. The method of employing solid carbon dioxide for refrigerating purposes comprising the 50 steps of gradually sublimating a mass of solid carbon dioxide, circulating the carbon dioxide gas formed through the unsublimated mass, condensing the circulating gas to form liquid carbon dioxide for cooling purposes by heat exchange with the unsublimated mass, and circulating the liquid carbon dioxide in heat exchange relation 55 with objects to be cooled.

4. In a refrigerating apparatus, the combination including a refrigerating chamber, a cooling coil in said chamber, a condenser coil connected to said cooling coil, a solid refrigerant container 60 enclosing said condenser coil, said condenser coil and container being in direct communication and said cooling and condenser coils having a readily vaporizable liquid therein, and thermostatic means connected to said cooling coil and controlled by the temperature conditions in said chamber for controlling the flow of liquid and vapor in the cooling coil.

5. In a refrigerating apparatus, the combination comprising a condenser coil and a cooling 70 coil connected together to provide a circulating system, a chamber to receive the cooling coil, a container for the condenser coil adapted to hold solid carbon dioxide, said condenser being open to the container, and means in the circulating system for insuring the delivery of wet vapor to

the cooling coil, said circulating system being provided to conduct a readily vaporizable liquid.

6. In a refrigerating apparatus of the type described, the combination with a condenser coil and a cooling coil connected together to provide a 80 circulating system, of a chamber for the condenser coil, said condenser coil communicating with the interior of the chamber, a cabinet within which the cooling coil is placed and a valve in the connection between the coils for controlling the supply of refrigerant to the cooling coil.

7. In a refrigerating apparatus of the type described, the combination comprising a condenser coil and a cooling coil connected together, a chamber for the condenser coil, the condenser coil communicating with the interior of the chamber, a cabinet for the cooling coil, and means connected ahead of the cooling coil for 85 insuring the delivery of wet vapors thereto.

8. In a refrigerating apparatus of the type described, the combination comprising a condenser coil and a cooling coil connected together, a chamber for the condenser coil to receive solid carbon dioxide, a connection between the interior of the chamber and the condenser coil, means in 90 said connection for withdrawing the gaseous carbon dioxide from the chamber and delivering it to the condenser coil, and a cabinet to receive the cooling coil.

9. In a refrigerating apparatus of the type described, the combination comprising a condenser coil and a cooling coil connected together, a chamber for the condenser coil to receive solid carbon dioxide, a connection between the interior of the chamber and the condenser coil, means in 100 said connection for withdrawing the gaseous carbon dioxide from the chamber and delivering it to the condenser coil, a cabinet to receive the cooling coil, and a float valve connected to the cooling coil for controlling the flow of liquid carbon dioxide thereto.

10. In a refrigerating apparatus of the type described, the combination comprising a condenser coil and a cooling coil connected together, a chamber for the condenser coil to receive solid 105 carbon dioxide, a connection between the interior of the chamber and the condenser coil, means in said connection for withdrawing the gaseous carbon dioxide from the chamber and delivering it to the condenser coil, a cabinet to receive the cooling coil, and a float valve connected to the cooling coil for controlling the flow of liquid carbon dioxide thereto.

11. A refrigerating method for effecting the cooling of a space or articles comprising the steps of sublimating a solid refrigerant within a confined space, conducting the vapor formed in close proximity to the unsublimated solid to condense the vapor into a liquid, evaporating the liquid within the space or near the articles to cool them and conducting the warm vapor adjacent the unsublimated solid to supply the heat of sublimation thereto.

12. In a refrigerating apparatus of the type described, the combination comprising a cabinet to be refrigerated, a chamber, a condensing coil within the chamber and open to the interior thereof, a cooling coil within the cabinet connected to the condenser coil, a control valve in the connection between the coils and a third coil connected to the outlet of the cooling coil, said 145

third coil being in heat exchange relation with said chamber.	refrigerant, which sublimes as the source for cooling relatively warm substances, the steps of producing cold gas from the solid by sublimation, condensing the gas, absorbing heat from the substance by heat transfer to the liquid and supplying the heat thus absorbed by the gas to effect further sublimation of the solid refrigerant.	80
13. In a refrigerating device as described, the combination comprising a chamber to receive a solid refrigerant, a condensing coil within said chamber and open to the interior thereof, a container providing a space to be refrigerated, a cooling coil in said container, a connection between condensing coils and the cooling coil including fluid control means for insuring the presence of vapor within the cooling coil, and a heating coil connected to the cooling coil and placed in heat exchange relation with respect to said chamber to supply heat thereto to effect evaporation of the solid refrigerant therein.	16. A method of preparing liquid carbon dioxide from solid carbon dioxide which comprises sublimating solid carbon dioxide to form carbon dioxide gas and circulating the carbon dioxide gas in heat exchange relation with the remaining solid to condense the gas to liquid form and supply heat for further sublimation of the solid.	85
14. In a method of preparing a liquid refrigerating medium from a solid refrigerating medium which sublimates, the steps of causing the solid refrigerant to gradually sublimate within a closed space and circulating the gas formed in heat exchange relation with the remaining solid and out of direct contact therewith to condense the gas to liquid form.	17. A method of preparing liquid carbon dioxide from solid carbon dioxide which comprises sublimating solid carbon dioxide to produce carbon dioxide gas, compressing the gas thus produced, circulating the compressed gas in heat exchange relation with the remaining solid to liquefy it by abstraction of the heat of compression from the gas and effecting further sublimation of the solid with the abstracted heat of compression.	90
15. In a refrigerating cycle employing a solid	JUSTUS C. GOOSMANN.	95
